UNITED STATES PATENT OFFICE.

SAMUEL T. HOBBS, OF WORCESTER, MASSACHUSETTS, ASSIGNOR TO HOBBS MANUFACTURING COMPANY, OF WORCESTER, MASSACHUSETTS, A CORPORATION OF MASSACHUSETTS.

SCORING-MACHINE.

1,184,853.

Specification of Letters Patent.

Patented May 30, 1916.

Application filed December 28, 1911. Serial No. 668,298.

To all whom it may concern:

Be it known that I, SAMUEL T. HOBBS, a citizen of the United States, residing at Worcester, in the county of Worcester and 5 Commonwealth of Massachusetts, have invented a new and useful Improvement in Scoring-Machines, of which the following is a specification, accompanied by drawings forming a part of the same.

10 My invention relates to that class of scoring machines which are used for scoring cardboard and the like, and particularly to the method of journaling the scoring disk.

15 The objects of my invention are to secure a more durable bearing for the scoring disk, to facilitate the removal of the disk, and to automatically take up any wear in the bearing of the disk so as to prevent the scoring disk from dropping into injurious contact 20 with the bed roll. I accomplish these objects by the construction and arrangement of parts as hereinafter described and pointed out in the annexed claims.

25 In the accompanying drawings I have represented so much of a scoring machine as is necessary to illustrate the character of my present invention.

30 Figure 1 is a side view of one of the brackets in which the scoring disk is supported, showing the transverse bearing to which the bracket is attached in sectional view and also showing the relative positions of the scoring disk and the bed roll. Fig. 2 35 is an edge view of the same. Fig. 3 is a detached perspective view of the retaining spring for holding the scoring disk in its bearings. Fig. 4 is a detached edge view of the scoring disk.

Similar reference characters refer to similar parts in the different figures.

40 In the accompanying drawings 1 denotes a dovetailed bar which extends transversely across the scoring machine and upon which are adjustably supported a series of brackets 45 2 by means of clamping screws 3. Connected with the bracket 2 is a V-shaped angle bar 4, capable of being adjusted on its connection with the bracket 2 by means of an adjusting screw 5. Journaled at the lower 50 corner of the angle bar 4 is a scoring disk or cutter 6, consisting of a steel disk having a sharpened edge and provided with gudgeons 7, 7 consisting of a bronze stud driven tightly into the scoring disk 6.

55 The angle bar 4 is recessed to receive the

scoring disk 6 and is provided with semi-circular journal bearings 8 to receive the gudgeons 7. A blade spring 9 is attached to the angle bar 4 by a screw 10. The blade spring 9 is bifurcated to form prongs 11, 11 which extend on either side of the scoring disk 6, and are bent upwardly at 12, 12 to press against the under side of the gudgeons 7 to hold the latter in close contact with the semicircular bearings 8. As the gudgeons 7 60 or the bearings 8 wear by continued use, the prongs 11, 11 of the spring 9 will take up the wear and maintain the gudgeons 7 in close running contact with their bearings. The relation of the scoring disk 6 to the 65 angle bar 4 is always maintained by the tension of the elastic prongs 11, 11 against the gudgeons 7. The tips of the elastic prongs 11, 11 are bent downwardly at 13, 13, Fig. 3, to enable the elastic prongs 11 to be expanded 70 by the pressure of the gudgeons 7 against the tips 13 when the scoring disk 6 is inserted in position in the angle bar 4.

75 The retaining spring 9 not only holds the scoring disk 6 in its highest position, but it 80 enables the disk to be readily removed and inserted without detaching the spring. By means of the adjusting screw 5, the angle bar 4 may be swung on its pivotal joint with the bracket 2 in order to adjust the position 85 of the scoring disk 6 relatively to a bed roll 14 and, as the scoring disk is always maintained in its highest position, the distance between the peripheries of the scoring disk 6 and the bed roll 14 may be delicately adjusted and constantly maintained. As the gudgeons 7 rotate with the scoring disk 6, the bearing surface is between the gudgeons 7 and the recesses 8 and is greater than the bearing surface of a scoring disk rotating on 90 a fixed pin, which is the common form of construction.

95 The bracket 2, adjustably supported upon the transverse dovetailed bar 1, and the angle bar 4, adjustably held in the bracket, 100 are substantially like the corresponding parts of scoring machines now in use. It has been the practice, however, to place a fixed pin in the angle bar 4 upon which the scoring disk was journaled, requiring the 105 withdrawal of the pin in order to remove the scoring disk. This form of construction limits the bearing surface of the scoring disk, soon causing lost motion between the pin and rotating disk. When the bearing 110

of the scoring disk became worn, it would fall by gravity into contact with the bed roll 14 and a delicate adjustment of the angle bar 4 failed to vary the position of the scoring disk which normally rested upon the bed roll. By my present improvement the scoring disk responds to the slightest movement of the angle bar, and is capable of being adjusted within a small distance of the bed roll and held permanently out of contact therewith.

I claim—

1. In a scoring machine, a bed roll, a framework fixed with relation to said bed roll and providing bearing recesses facing the surface of said bed roll, a scoring disk for coöperation with said bed roll having gudgeons disposed in said recesses and projecting beyond the same, and a spring bearing against said gudgeons on opposite sides

of said disk to retain said gudgeons yieldingly within said recesses, the tip of said spring being curved away from said recesses, for the purpose specified.

2. In a scoring machine, a bed roll, a fixed frame-work, a scoring disk having oppositely extending gudgeons, carried by said framework, said framework providing bearing recesses for said gudgeons of less depth than said gudgeons, and a spring bearing against said gudgeons to retain the same yieldingly within said recesses, whereby the wear between said gudgeons and said recesses is automatically taken up.

Dated this 22nd day of December, 1911. 35

SAMUEL T. HOBBS.
